UNITED STATES PATENT OFFICE.

ARTHUR EDWARD CUTLER AND PHILIP ALLAN MARSDEN, OF NEWCASTLE,
AUSTRALIA.

APPARATUS FOR FORMING OR SHAPING ARTICLES FROM SHEET MATERIAL.

Application filed February 20, 1925. Serial No. 10,524.

To all whom it may concern:

Be it known that we, ARTHUR EDWARD CUTLER and PHILIP ALLAN MARSDEN, both British subjects, and both residing at Walsh 5 Island, Newcastle, in the State of New South Wales, Commonwealth of Australia, have invented certain new and useful Improvements Relating to the Apparatus for Forming or Shaping Articles from Sheet Material, of which the following is a specification.

This invention relates to a method and apparatus of forming or shaping articles made from sheet material such as metal, 15 leather, plastic or fibrous materials, or other substance capable of being so formed, by fluid pressure which forces the sheet into or onto a die or the like which may have a recess or cavity of the shape to be imparted 20 to the sheet, or may be a partial or composite die or a frame or open topped structure comprising an upper ring or other shaped support to grip the work sheet in a yielding manner, in which frame the pressure 25 will act radially and symmetrically outwards.

In this method of forming or shaping articles as hitherto practised a flexible container or bag has been employed and the 30 fluid pressure admitted thereto; or alternatively a flexible sheet was interposed between the fluid pressure and the sheet to be shaped. The container or bag and the flexible sheet were both liable to sustain 35 damage and perhaps fail at a critical stage; also the said bag or sheet could not be forced into sharp corners, and were costly and difficult to operate, the practicable pressure and therefore the range of manufacture 40 being limited by the strength of the bag or sheet. Furthermore, deep articles such as stew-pans and washing boilers could not be formed by a single pressing operation in this way, several successive pressing operations being necessary.

According to the present invention the "fluid-pressure" (which expression is intended to include pressure by gases or vapours as well as pressure by liquids such as 50 water, oil, mercury, tar, spirits, liquid compositions or liquid cement) is applied directly through a chambered or other block to one side of the work sheet without the interposition or employment of a flexible

bag or sheet, and a grummet or packing 55 piece is employed at the joint or meeting edges of the die and block, which may be for example a closed ring of rubber tubing, or in some cases may be leather or other flexible material of U section with the opening facing inwardly, and the block may be grooved or recessed to accommodate this grummet. The grummet is pressed by the fluid pressure against the surface of the sheet to be shaped and against the surface 60 of the block, thus preventing escape of fluid between the surface of the block and the sheet. A chamber may be formed in the block, which chamber is in communication with a pressure supply pipe, and is also connected with a valved exhaust pipe; but if the block be close to the underside of the work sheet the pressure when first admitted 65 will immediately lift up the part of the work sheet opposite the pressure admission opening, so that the pressure will then be evenly distributed over the underside of the work sheet.

The forming die and block are arranged 70 to be movable in relation to each other so that the sheet to be operated upon may be inserted and the finished article removed. Means of any known or suitable type can be provided for moving one of the parts and for holding the parts in operative position 75 and in proper relation and register when the work sheet has been inserted. Such means must obviously be capable of resisting the fluid pressure. The opposing holding surfaces between the die and block, 80 which may be termed "ironing surfaces," or one of these surfaces, should usually be supported in a manner which will permit 85 of some resiliency between them, so that although the work sheet is held between them with sufficient tightness, the edges of the work sheet can creep or slip inwardly 90 when the pressure is applied, instead of being drawn thinner so that the thickness 95 of the article made becomes uneven.

In order that the said invention may be 100 clearly understood and readily carried into effect, the same will now be described more fully with reference to the accompanying diagrams, which illustrate an embodiment 105 of the invention as one example of the many ways in which it can be put in practice, and in which:—

Figure 1 represents in section a block and die with a sheet of material ready to be pressed.

Figure 2 represents in section the same parts with the material pressed to the shape of the die.

A indicates the block, which is formed with a pressure chamber B, around which chamber is a groove C. An opening D in the block communicates with a suitable pipe (not shown) connected with a source of fluid pressure. Such pipe may be branched and have on one branch a valve controlling the admission of the fluid under pressure, and on the other branch a valve which on being opened allows the said fluid to escape or be withdrawn. E indicates the die, which is provided with an air relief duct F, and G indicates the sheet material under operation. A ring H of flexible material such as a closed rubber tube is fitted in the groove C. The sheet material is exposed to pressure from its underside, the extent of which pressure and the time during which it is applied will of course vary according to circumstances, such as the strength or thickness and the physical characteristics of the material under treatment. The packing ring will alter in shape during the pressing operation more or less in the manner represented in Figure 2. The shaping operation obviously causes compression of the material treated where a die is used, and may either cause compression or expansion of certain parts of the material where the die is replaced by an open-topped frame.

Although we have illustrated the die as being placed above the block, as this position will usually be the most convenient one, the relative positions of the die and block are immaterial; the ironing surfaces of the

die may for instance be vertical, that is, the die may be alongside the block instead of above it.

The invention is applicable to the manufacture of a great variety of articles, for example, saucepan lids, felt hats, fibre trunks, motor-car bodies and mud-guards, embossed leather articles, ceiling ornaments, embossed advertisements, name plates for street-corners, number-plates for motor vehicles. In the latter class of applications the die may be made of several pieces, interchangeable and relatively adjustable in order to facilitate the arrangement of the printing characters. The die may be concave, convex, or corrugated, and may be adapted to incorporate in the work sheet reinforcing or ornamental substances, as in the manufacture of reinforced cement blocks in the manufacture of felt hats with silk facings, or to strengthen dentures with metal stiffeners.

What we claim and desire to secure by Letters Patent of the United States is:—

An apparatus for shaping articles from sheet material comprising a die member, a block having a pressure chamber, said die member and block adapted to yieldingly secure the sheet material between them, means for admitting fluid pressure to said chamber to act directly on one side of the sheet material, said block having a groove at the edge adjacent the pressure chamber, and a closed flexible tubular gasket fitting in said groove and adapted to be subjected to the action of a fluid pressure and to have its contour altered by said pressure to maintain a sealing action against the sheet material and prevent leakage of the fluid pressure.

ARTHUR EDWARD CUTLER.
PHILIP ALLAN MARSDEN.
